UNITED STATES PATENT OFFICE.

JOHN F. COOLEY, OF BOSTON, MASSACHUSETTS, ASSIGNOR TO CHARLES F. WEED, RECEIVER, OF BROOKLINE, MASSACHUSETTS.

ROTARY ENGINE.

No. 833,676.

Specification of Letters Patent.

Patented Oct. 16, 1906.

Application filed March 5, 1906. Serial No. 304,190.

To all whom it may concern:

Be it known that I, JOHN F. COOLEY, a citizen of the United States, and a resident of Boston, in the county of Suffolk and State of 5 Massachusetts, have invented new and useful Improvements in Rotary Engines, of which the following is a specification.

My invention relates to rotary engines; and it consists in certain structural improvements by which the engine is rendered economical of power, highly effective in contrast to the size and weight of the parts employed, wear-resisting, durable, and simple.

In the drawings hereto annexed, which 15 illustrate an embodiment of my invention, Figure 1 is a side elevation of an engine with one of the heads and a cheek-plate removed. Fig. 2 is a vertical longitudinal section of the engine cylinder and heads, showing the rotative parts in elevation. Fig. 3 is a side elevation of one of the cheek-plates, and Fig. 4 is a side elevation showing the interior of one of the heads with the engine-shaft in cross-section.

25 The type of engine to which my improvements are applied, as illustrated in the drawings, is that characterized by a radially-slotted disk or spider secured to the engine-shaft, which is mounted eccentrically to rotate 30 within a cylinder and carrying in the radial slots the radially-moving pistons, which by contact with the interior surface of the cylinder serve as pistons to receive the expansive effort of admitted steam. Moreover, for the 35 sake of simplicity and strength I have adopted the cylindrical roller form of pistons, which by reason of their rolling friction upon the cylinder as distinguished from the scraping or rotating friction of wings or vanes of other 40 sorts inflict but little abrasion and wear upon the cylinder, which reciprocally wears the rollers but little.

The cylinder A is provided with a steam-port a^2 and an exhaust-port a^3 and is peripherally chambered at a a' , the chamber a communicating with the steam-inlet port a^2 and the chamber a' with the exhaust-port a^3 . The internal webs a^4 divide these peripheral steam-chambers from one another. The two 45 ends of the cylinder A are bored out at a^9 , so as to provide seats for the cheek-plates a^5 , and steam-inlet passages a^{11} and exhaust-passages a^{13} are formed by drilling longitudi-

nally through the material of the cylinder into the peripheral chambers a and a' , respectively. The cylinder-heads a^6 are preferably made duplicates of each other and are counterbored at a^8 to correspond with the counterbore a^9 of the cylinder-head A and are still further counterbored at a^{14} to provide 55 cylindrical chambers for the accommodation of the roller-bearings a^{15} , presently to be described. Bolts a^7 pass through the cylinder-heads and suitable lugs formed upon the cylinder, and when the cheek-plates are set in 60 the cavities formed by the opposite counterbores a^9 and a^8 and the plates a^7 are set up the cheek-plates are then and by this means clamped securely to the cylinder. The shaft 70 c passes through the cylinder-heads and cylinder, with its axis eccentric to the cylinder-bore. The spider B is secured by any desired mode to the shaft c , and roller-pistons C are placed in the slots c of the spider-ring B. The bosses a^{16} of the cylinder-heads a^6 are 75 threaded, so as to receive the adjustable hollow cap or stuffing-box in the usual manner.

One of the cheek-plates a^5 (or, if desired, both of these) is formed with depressions or holes a^{10} a^{12} , which register with the steam-opening a^{11} and the exhaust-openings a^{13} , respectively. The cavity a^{10} has formed in communication with it the lead-port a^{102} and the follower-port a^{101} , which perform an office 80 presently to be described.

As the rotative speed of a rotary engine is very much higher than that of a reciprocating engine of approximately the same power, the centrifugal throw of the roller-pistons C is a considerable factor, and while with very 90 small engines it may be admissible practice to make these roller-pistons solid, it is preferable in all cases and almost essential in larger engines to reduce the weight of the piston-rollers C as much as possible, and for this reason I employ for these rollers hollow cylinders securely headed at their ends, and thus 95 reduce even that rolling friction which is practically the only source of wear to which the cylinder is subjected.

The shaft c is mounted and rotates upon the roller-bearings a^{15} , which are arranged in the cylindrical chamber a^{14} in the cylinder-heads. These roller-bearings consist of steel rings, and in order to dispense with the 100 expense and complication of special ball or 105

roller races I employ rollers a^{15} , which bear directly upon the shaft c at one side and upon the interior of the chamber a^{14} at the other. For this purpose if the rollers a^{15} are made of the same diameter as the shaft c six of these rollers can be conveniently arranged in the roller-chambers a^{14} and serve admirably to reduce the friction due to the rotation of the parts. The employment of rings instead of balls or solid rollers affords a slight degree of play, due to the greater elasticity of these rings, than could be obtained from balls or solid rollers, so that in addition to the anti-friction-bearing I secure also the benefit of what is in substance a spring suspension, though of course the possible scope of actual movement of such springs is very slight.

The cylindrical recesses a^{14} are relatively quite large, having a diameter substantially equal to that of the spider B, so that in addition to serving as an annular raceway for the roller-bearings a^{15} this chamber assists in equalizing the expansions of the cylinder-heads and cheek-plates by affording an external chamber into which steam may penetrate and jacket the ends of the engine.

In the operation of the engine each two consecutive roller-pistons C constitute the front and rear abutments against which the expansive effort of the steam reacts, and as the space included between two consecutive roller-pistons, the outer cylinder-wall, and the surface of the spider B can only enlarge by rotation of the spider D and its attached shaft c steam admitted to this space causes the spider and shaft to rotate. In order to insure effective contact between the roller-piston C and the internal wall of the cylinder A, the hollow steam-port cavity a^{10} , formed in the cheek-plate a^5 , is made to extend toward the shaft c a sufficient distance to admit steam into the spider-slots c' inside the roller-piston C. Ordinarily when the engine is in full operation the centrifugal throw of the roller-piston C will be sufficient to hold them in contact with the wall of the cylinder A; but should the rate of rotation be slow or the engine be standing still the admission of steam behind the piston will be effectual to insure this necessary contact. For this purpose also the lead and follower extension-ports a^{102} and a^{101} are provided, the angular distance between the extreme ends of these two supplemental ports being sufficient to span the space between two consecutive piston-slots c' . Thus if the engine be standing still steam on being admitted will pass through the lead-port or follower-port, or both, and throw the two piston-cylinders C, which are for the time being the effective pair, into contact with the cylinder-wall and incidentally place the engine in economical operative condition. The cylinder A, spider B, and roller-piston C are so proportioned that the lateral surfaces of the spider and

roller-pistons shall nearly, but not quite, fill the space longitudinally between the cheek-plates a^5 , the clearance being so slight that the plane surfaces of the spider B and the ends of the roller-pistons shall be steam-packed in relation to the cheek-plates a^5 . This clearance, however, is sufficient to permit the gradual penetration of steam of the several cavities in the engine-casing and engine-head, so that not only shall the cheek-plates a^5 be steam-jacketed by the cylindrical cavities a^{14} , but also the spider B and piston-rollers C shall be held balanced in the cylinder. The suspension of the engine-shaft upon the rollers a^{15} relieves the shaft of all bearing friction, except such as may be incident to the necessary packing of the two ends of the shaft. By attaching a lubricator to the steam-supply pipe enough oil is carried into the engine to lubricate the roller-piston C and roller-bearings a^{15} sufficiently for all working purposes.

The effect of the roller-pistons C traveling in rolling contact upon the inner cylinder-wall is merely to polish the cylindrical surface until they acquire a mirror finish. Examination of engines of this character which have been in use for several months shows that only these cylindrical surfaces and also the cylindrical surfaces of the cavities a^{14} and roller-bearings a^{15} show the effect of wear; but the cheek-plates a^5 are not worn, showing that the effect of balanced steam-pressure within the cylinder is fully obtained. Moreover, the rolling friction of the piston C upon the cylinder A does not develop any perceptible wear other than that evidenced by the polished surfaces after several months continuous use.

The exhaust-cavity a^{12} occupies about twice as much angular distance as the steam-admission cavity a^{10} and operates to open the exhaust cumulatively as each piston C passes from one end to the other of the exhaust-cavity, so that as the space between the spider B, cylinder A, and two consecutive pistons C is contracting the exhaust-relief proportionately increases its capacity. Leading from the exhaust depression a^{12} is a duct a^{103} , passing through the cheek-plate a^5 and communicating with the roller-bearing chamber to admit steam into said chamber for the purpose of steam-jacketing the ends of the engine and also assisting to lubricate the roller-bearings.

It will be observed by referring to Fig. 3 that as the steam-admission cavity a^{10} extends inward radially to a point inside the piston-roller C a spot a^{104} is provided whose surface is flush with the surface of the cheek-plate a^5 , so that at no time can roller C lose its proper bearing or position and collide with the edges of the cavity a^{10} . The exhaust-cavity a^{12} has its inner edge located farther from the center than the innermost ports of

the roller-pistons, so that here again there is no opportunity for these pistons to become dislodged from their proper positions with reference to the cylinder and cheek-plates a⁵.

5 I claim as my invention—

1. In a rotary engine, the combination of an annular cylinder provided with a steam-inlet, a steam-outlet and longitudinal perforations communicating respectively with the

10 said inlet and outlet, cheek-plates bored to admit the rotor-shaft and provided with hollows registering respectively with the steam and exhaust perforations of the cylinder, a rotor consisting of a radially-slotted disk mounted on a shaft, the said shaft eccentrically mounted in the cylinder, roller-pistons in the radial slots of the disk, cylinder-heads, and means to clamp the same against the cheek-plates to bind said cheek-plates

15 against the cylinder, said heads being longitudinally bored to admit the rotor-shaft.

2. In a rotary engine, the combination of an annular cylinder provided with a steam-inlet, a steam-outlet and longitudinal perforations communicating respectively with the

25 said inlet and outlet, cheek-plates bored to admit the rotor-shaft and provided with hollows registering respectively with the steam and exhaust perforations of the cylinder, the

30 steam-admission hollow provided with lead and the follower extension-ports, a rotor consisting of a radially-slotted disk mounted on a shaft, the said shaft eccentrically mounted in the cylinder, roller-pistons in the radial

35 slots of the disk, cylinder-heads, and means to clamp the same against the cheek-plates to bind said cheek-plates against the cylinder, said heads being longitudinally bored to admit the rotor-shaft.

40 3. In a rotary engine, the combination of an annular cylinder provided with a steam-inlet, a steam-outlet and longitudinal perforations communicating respectively with the said inlet and outlet, cheek-plates bored to

45 admit the rotor-shaft and provided with hollows registering respectively with the steam and exhaust perforations of the cylinder, the steam-admission hollow provided with lead and the follower extension-ports, said steam-

50 admission hollow extending radially to a point inside the path of the roller-pistons, a rotor consisting of a radially-slotted disk mounted on a shaft, the said shaft eccentrically mounted in the cylinder, roller-pistons in the

55 radial slots of the disk, cylinder-heads, and means to clamp the same against the cheek-plates to bind said cheek-plates against the cylinder, said heads being longitudinally bored to admit the rotor-shaft.

60 4. In a rotary engine the combination of an annular cylinder provided with a steam-inlet, a steam-outlet and longitudinal perforations communicating respectively with the said inlet and outlet, cheek-plates bored to

65 admit the rotor-shaft and provided with hol-

lows registering respectively with the steam and exhaust perforations of the cylinder, the steam-admission hollow provided with lead and the follower extension-ports, said steam-admission hollows extending radially to a point inside the path of the roller-pistons, a spot in said steam-hollow flush with the surface of the cheek-plate and lying in the path of the roller-pistons, the exhaust-hollow having its inner boundary outside of the inner edge of the path of the roller-pistons, a rotor consisting of a radially-slotted disk mounted on a shaft, the said shaft eccentrically mounted in the cylinder, roller-pistons in the radial slots of the disk, cylinder-heads, and means to clamp the same against the cheek-plates to bind said cheek-plates against the cylinder said heads being longitudinally bored to admit the rotor-shaft.

5. In a rotary engine the combination of 85 an annular cylinder provided with a steam-inlet, a steam-outlet and separated peripheral jacket-cavities, one communicating with the steam-inlet and the other with the steam-

40 outlet and with longitudinal perforations from the said jacket-cavities, cheek-plates eccentrically bored to admit the rotor-shaft and provided with hollows registering with the steam and exhaust perforations respec-

45 tively, a rotor consisting of a radially-slotted disk secured to a shaft eccentrically mounted with respect to the cylinder, roller-pistons in the disk-slots, cylinder-heads, and means to clamp the same against the cheek-plates to bind the latter to the cylinder, said heads be-

50 ing longitudinally bored to admit the rotor-shaft.

6. In a rotary engine the combination of 95 an annular cylinder provided with a steam-inlet, a steam-outlet and separated peripheral jacket-cavities, one communicating with the steam-inlet and the other with the steam-

100 outlet and with longitudinal perforations from the said jacket-cavities, cheek-plates bored to admit the rotor-shaft and provided with hollows registering respectively with the steam and exhaust perforations of the cylinder, the steam-admission hollow pro-

105 vided with lead and the follower extension-ports, a rotor consisting of a radially-slotted disk secured to a shaft eccentrically mounted with respect to the cylinder, roller-pistons in the disk-slots, cylinder-heads, and means to clamp the same against the cheek-plates to bind the latter to the cylinder, said heads be-

110 ing longitudinally bored to admit the rotor-shaft.

7. In a rotary engine the combination of 115 an annular cylinder provided with a steam-inlet, a steam-outlet and separated peripheral jacket-cavities, one communicating with the steam-inlet and the other with the steam-

120 outlet and with longitudinal perforations from the said jacket-cavities, cheek-plates bored to admit the rotor-shaft and provided with hollows registering respectively with the steam and exhaust perforations of the cylinder, the steam-admission hollow pro-

125 vided with lead and the follower extension-ports, a rotor consisting of a radially-slotted disk secured to a shaft eccentrically mounted with respect to the cylinder, roller-pistons in the disk-slots, cylinder-heads, and means to clamp the same against the cheek-plates to bind the latter to the cylinder, said heads be-

130 ing longitudinally bored to admit the rotor-shaft.

with hollows registering respectively with the steam and exhaust perforations of the cylinder, the steam-admission hollow provided with lead and follower extension-ports, 5 said steam-admission hollow extending radially to a point inside the path of the roller-pistons, a rotor consisting of a radially-slotted disk secured to a shaft eccentrically mounted with respect to the cylinder, roller-10 pistons in the disk-slots, cylinder-heads, and means to clamp the same against the cheek-plates to bind the latter to the cylinder, said heads being longitudinally bored to admit the rotor-shaft.

15 8. In a rotary engine the combination of an annular cylinder provided with a steam-inlet, a steam-outlet and separated peripheral jacket-cavities, one communicating with the steam-inlet and the other with the steam-20 outlet and with longitudinal perforations from the said jacket-cavities, cheek-plates bored to admit the rotor-shaft and provided with hollows registering respectively with the steam and exhaust perforations of the cylinder, the steam-admission hollow provided with lead and follower extension-ports, 25 said steam-admission hollow extending radially to a point inside the path of the roller-pistons, a spot in said steam-hollow flush 30 with the surface of the cheek-plate and lying in the path of the roller-pistons, the exhaust-hollow having its inner boundary outside of the inner edge of the path of the roller-pistons, a rotor consisting of a radially-slotted disk secured to a shaft eccentrically 35 mounted with respect to the cylinder, roller-pistons in the disk-slots, cylinder-heads, and means to clamp the same against the cheek-plates to bind the latter to the cylinder, said 40 heads being longitudinally bored to admit the rotor-shaft.

9. In a rotary engine the combination of an annular cylinder provided with a steam-inlet, a steam-outlet and peripheral separated jacket-cavities communicating with the steam-inlet and steam-outlet respectively, 45 the ends of the cylinder counterbored to admit cheek-plates and the cylinder provided with perforations extending from the jacket-50 cavities to the counterbored portions, cheek-plates fitted to and seated in the cylinder-counterbores and eccentrically bored to admit the rotor-shaft, said cheek-plates provided also with hollows registering with the 55 steam and exhaust perforations of the cylinder respectively, a rotor consisting of a radially-slotted disk secured to a shaft eccentrically mounted in the cylinder, roller-pistons working in the disk-slots, cylinder-heads, and 60 means to clamp the same against the cheek-plates to secure the latter to the cylinder and bored to admit the rotor-shaft.

10. In a rotary engine the combination of an annular cylinder provided with a steam-65 inlet, a steam-outlet and peripheral sep-

rated jacket-cavities communicating with the steam-inlet and steam-outlet respectively, the ends of the cylinder counterbored to admit cheek-plates and the cylinder provided with perforations extending from the jacket-cavities to the counterbored portions, cheek-plates fitted to and seated in the cylinder-counterbores and eccentrically bored to admit the rotor-shaft, said cheek-plates provided also with hollows registering with the steam and exhaust perforations of the cylinder respectively, the steam-admission hollow provided with lead and follower extension-ports, a rotor consisting of a radially-slotted disk secured to a shaft eccentrically mounted in the cylinder and roller-pistons working in the disk-slots, cylinder-heads, means to clamp the same against the cheek-plates to secure the latter to the cylinder and bored to admit the rotor-shaft.

11. In a rotary engine the combination of an annular cylinder provided with a steam-inlet and a steam-outlet and peripheral separated jacket-cavities communicating with the steam-inlet and steam-outlet respectively, the ends of the cylinder counterbored to admit cheek-plates and the cylinder provided with perforations extending from the jacket-cavities to the counterbored portions, cheek-plates fitted to and seated in the cylinder-counterbores and eccentrically bored to admit the rotor-shaft, said cheek-plates provided also with hollows registering with the steam and exhaust perforations of the cylinder respectively, the steam-admission hollow provided with lead and follower extension-ports and a spot in the steam-admission hollow flush with the surface of the cheek-plate and lying in the path of rotation of the piston-rollers, a rotor consisting of a radially-slotted disk secured to a shaft eccentrically mounted in the cylinder, roller-pistons working in the disk-slots, cylinder-heads, and means to clamp the same against the cheek-plates to secure the latter to the cylinder and bored to admit the rotor-shaft.

12. In a rotary engine the combination of an annular cylinder provided with a steam-inlet and a steam-outlet and peripheral separated jacket-cavities communicating with the steam-inlet and steam-outlet respectively, the ends of the cylinder counterbored to admit cheek-plates, and the cylinder provided with perforations extending from the jacket-cavities to the counterbored portions, cheek-plates fitted to and seated in the cylinder-counterbores and eccentrically bored to admit the rotor-shaft, said cheek-plates provided also with hollows registering with the steam and exhaust perforations of the cylinder respectively, the steam-admission hollow provided with lead and follower extension-ports and a spot in the steam-admission hollow flush with the surface of the cheek-plate and lying in the path of rotation of the pis-130

and the cylindrical periphery of the counterbores in said heads bearing directly upon the shaft and the counterbored peripheries.

18. In a rotary engine the combination of
 5 an annular cylinder provided with a steam-inlet and a steam-outlet and peripheral separated jacket-cavities communicating with the steam-inlet and steam-outlet respectively, the ends of the cylinder counterbored
 10 to admit cheek-plates and the cylinder provided with perforations extending from the jacket-cavities to the counterbored portions, cheek-plates fitted to and seated in the cylinder-counterbores and eccentrically bored to
 15 admit the rotor-shaft, said cheek-plates provided also with hollows registering with the steam and exhaust perforations of the cylinder respectively, the steam-admission hollow provided with lead and follower extension-ports, and a spot in the steam-admission hollow flush with the surface of the cheek-plate and lying in the path of rotation of the piston-rollers, the exhaust-hollow having its inner margin outside of the inner edge of the path
 20 of the roller-pistons, a rotor consisting of a radially-slotted disk mounted on the shaft, the said shaft eccentrically mounted in the cylinder, roller-pistons in the radial slots of the disk, said roller-pistons being hollow and headed at the ends, cylinder-heads, means to clamp the same against the cheek-plates to bind said cheek-plates against the cylinder, said heads longitudinally bored to admit the rotor-shaft, said heads counterbored around the shaft-bearing, said counterbores being substantially of the same diameter as the radially-slotted disk of the rotor, and roller-bearings between the shaft and the cylindrical periphery of the counterbores in said
 25
 30
 35

heads bearing directly upon the shaft and the 40 counterbored peripheries, the said roller-bearings consisting of annular resilient cylinders.

19. In a rotary engine the combination of
 an annular cylinder provided with a steam- 45 inlet and a steam-outlet and longitudinal perforations communicating respectively with the said inlet and outlet, cheek-plates bored to admit the rotor-shaft and provided with hollows registering respectively with the 50 steam and exhaust perforations of the cylinder, a rotor consisting of a radially-slotted disk mounted on a shaft, the said shaft eccentrically mounted in the cylinder, roller-pistons in the radial slots of the disk, said roller-pistons being hollow and headed at the ends, cylinder-heads, means to clamp the same against the cheek-plates to bind said cheek-plates against the cylinder, said heads longitudinally bored to admit the rotor-shaft, said 55 heads counterbored around the shaft-bearing, said counterbores being substantially of the same diameter as the radially-slotted disk of the rotor, and roller-bearings between the shaft and the cylindrical periphery of the 60 counterbores in said heads bearing directly upon the shaft and the counterbored peripheries, and a steam-inlet port leading from the exhaust-hollow of the cheek-plate to the roller-bearing chamber within the counter- 65 bore of the cylinder-head.

Signed by me at Boston, Massachusetts,
